UNITED STATES PATENT OFFICE.

BURTON W. SWEET, OF CLEVELAND, OHIO, ASSIGNOR TO THE VAN DORN ELECTRIC TOOL COMPANY, OF CLEVELAND, OHIO, A CORPORATION OF OHIO.

BRUSH-HOLDER FOR DYNAMO-ELECTRIC MACHINES.

1,307,028.

Specification of Letters Patent. Patented June 17, 1919.

Application filed August 7, 1915. Serial No. 44,208.

To all whom it may concern:

Be it known that I, BURTON W. SWEET, a citizen of the United States of America, residing at Cleveland, in the county of Cuyahoga and State of Ohio, have invented certain new and useful Improvements in Brush-Holders for Dynamo-Electric Machines, of which the following is a specification.

- 10 My invention relates to improvements in brush holders for dynamo electric machines, and has for its object, the construction of a compact and simple brush holder especially designed for multi-polar machines, which 15 will permit of readily inserting and removing the brushes while insuring adequate conductivity, as well as maintaining the desired pressure or tension upon said brushes. Other structural features will be explained 20 in connection with the preferred embodiment of my invention which is disclosed in a brush holder for accommodating some four carbon brushes and maintaining them in contact relation with the commutator.
- 25 The features of this device will be better understood by first making reference to the accompanying sheet of drawings, wherein:

Figure 1 is a front view of the multi-polar brush holder device embodying my invention,

Fig. 2 is a rear view thereof, and

Fig. 3 is a fragmentary view upon a larger scale with the parts partially broken away.

35 Fig. 4 is another enlarged fragmentary edge-view of said brush holder. Fig. 5 is a cross-sectional detail.

The same character of reference is employed throughout the figures to indicate 40 similar parts.

The annual insulating base *a* of my device pivotally mounts four spring-pressed arms *b*, which respectively are associated with the stationary guides *c* for accommodating 45 their flat carbon brushes *d*. These brushes *d* are shown in Figs. 1 and 2 in position of yieldingly engaging the commutator *e*.

Each of said arms *d* is mounted upon a pivot pin *f*; these being diametrically positioned in opposing pairs. The upper and lower pivot pins, as will be noted by referring to Fig. 2, are electrically connected by means of a conductor *f'* embedded in the inwardly channeled, annular cover-member *g*, while the horizontally extending pivot

pins are electrically connected by means of the conductor *f''*, also embedded in said annular cover-member; these conductors being disposed in separate concentric channels as shown by full and dotted lines.

60

As will be better understood by referring to Figs. 3 and 4, each of said pivot pins is equipped with a coiled spring *h*, having an outer terminal pin *h'*, adapted to be seated in any of the numerous depressions *b'*, provided about the hub of the arm *b*. Thus, the tension of the spring in its re-action against said arm, may be readily adjusted for the purpose of depressing the individual brush within its holder, while the conductivity of the pivoted parts is enhanced by means of the rectangularly bent inner terminal *h''* of said spring, which is clamped within the slot *f''* longitudinally cut in the pivot pin.

65

70 The brush *d* is provided with a permanently connected flexible conductor *d'*, which is adapted to complete the connection through the arm *b* by means of a terminal pin *d''*, which may be inserted within the bored receptacle *b''* provided upon the arm *b*, and mounted between its side pieces *b*². An interiorly positioned spring *b*³ is adapted to be depressed and engage the end of said terminal pin upon its insertion within the receptacle 80 whereby contact is established directly with the brush. By this arrangement, the brushes may be readily renewed, while securing the advantages of a permanent connection with the spring actuated arm. Moreover, as the 85 brushes are capable of partial removal from the guides, they may be held out of engagement with the commutator by elevating them as shown in Fig. 3, and permit the arm to bear laterally against said brushes, instead of upon their ends, so that the commutator may be inspected and any necessary attention given thereto, and to the brushes themselves, without actually removing said 90 brushes from the holder.

95

95 While the brush may be elevated out of contact with the commutator, as just explained, it is not necessary to disconnect the terminal *d''* and the conductor *d'* from the arm. Thus, the device may be promptly restored to its working condition, as shown in Figs. 1 and 2. From a consideration of the structure just described, it will be seen that unusually effective contact is insured between the conductive parts, inasmuch as 100

100

105 From a consideration of the structure just described, it will be seen that unusually effective contact is insured between the conductive parts, inasmuch as 110

spring tension and wide bearing-surfaces are utilized throughout for the maintenance of electrical conductivity. First, the conductors f' , f'' , are embedded in annular channels within the insulating member, to electrically unite the rear extensions f^3 , f^4 , of the pivot pins. These pivot pins, in turn, are terminally engaged by the coil springs h , which respectively place the pivot-arms under tension. The arms, in turn, have spring and plug connections with the conductors attached to the several brushes, so that no defective connections are possible throughout the device.

15 Referring particularly to Figs. 4 and 5, the means for initially adjusting the tension of the coil spring h , will be readily understood. The sleeve i , is stationary with the base, while the screw-headed pivot pin f , is 20 rotatable therein. Quartered holes, f^5 , are bored in the shank of said pivot-pin, while a spring-key, k , is adapted to pass through said holes when in register with corresponding holes i' , bored in said sleeve. By using 25 a screw-driver, and rotating the pivot in a clockwise direction, an initial tension of any desired amount may be placed upon the spring h , suitable to the particular requirements, with the pin h'' engaging the outer 30 slot of the arm b . As the brushes wear away, the pin h'' , may be moved back successively, into the four additional depressions therefor in the hub of the pivot arm, corresponding to the wear of the brush, so 35 that the given set of tension spring h , upon the pivot pin, need not be altered.

Accordingly, my improved brush-holder, which is adapted for dynamo-electric machines of moderate size, and for small electric tools, requires less adjustment and attention than other similar devices, and more readily lends itself to prompt adjustment, and for giving attention to the commutator, than do other brush-holders with which I 45 am acquainted. The brushes may be quickly raised or lowered in their respective guides or sockets, and the individual tension of their springs may be set to conform with the conditions of wear, so that brushes of different lengths may be used with equal facility.

Having now described the preferred embodiment of my invention, I claim as new, and desire to secure by Letters Patent, the following:—

55 1. In a brush-holder device, the combination with a socket-member for receiving a brush, of a pivoted arm adapted normally to bear against the end of the inserted brush, a flexible conductor connecting the arm and

said brush, a tension spring controlling the pressure of said arm on the brush and means for adjusting said tension spring from both of its extremities substantially as set forth.

2. In a brush-holder device, the combination with an insulating annular base, of diametrically positioned brush holding members and two conductors respectively connecting the diametrically positioned brush holding devices; said insulating base being formed with separate annular grooves, 70 adapted respectively to receive and insulate said conductors, substantially as set forth.

3. In a brush-holding device, the combination with an insulating base, of a brush-holder and socket, wherein the brush is 75 adapted freely to slide, a pivoted arm adjacent to said socket and positioned alternatively to bear against the end of the inserted brush, or against its side, when said brush is partially withdrawn, and a tension spring 80 for exerting pressure through said arm upon the brush, substantially as set forth.

4. In a brush-holder for dynamo electric machines, the combination with a guide for supporting the brush, of a brush loosely 85 sliding therein, a spring-actuated arm reacting against the brush, a flexible conductor connecting the arm and said brush, means for adjusting the initial tension of said arm and additional means for compensating the 90 wear of the brush, whereby to obtain substantially uniform pressure upon a commutator, substantially as set forth.

5. In a brush-holder for dynamo electric machines, the combination with a guide for 95 supporting the brush, of a spring actuated arm reacting against the brush, a coiled spring adjustably attached to said arm, adjustable attaching means and independent means for placing an initial tension upon 100 said spring, comprising a rotatable detent for the inner end of the spring and a securing part for said detent, substantially as set forth.

6. In a brush-holder device, the combination with a brush-receiving member, of a pivoted arm adapted normally to bear upon the brush, a tension spring therefor, and means for adjusting the spring tension from both of its extremities, substantially as set 110 forth.

In testimony whereof I do hereby affix my signature in the presence of two witnesses.

BURTON W. SWEET.
